CLAIM

The ornamental design for a respiratory trainer, as shown and described.

DESCRIPTION

FIG. 1 is a front elevation view of a respiratory trainer in a first orientation showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a perspective view thereof;
FIG. 8 is another perspective view thereof; and,
FIG. 9 is a perspective view of the respiratory trainer in a second orientation.
The broken lines depict portions of the respiratory trainer that form no part of the claimed design.

1 Claim, 9 Drawing Sheets
